UNITED STATES PATENT OFFICE.

JOHN MARTIN DEAGLE, OF CATARACT, TOWNSHIP OF CALEDON, ONTARIO, CANADA

CLOTHES WRINGER

Application filed August 5, 1924. Serial No. 730,250

This invention relates to a wringer, power or manually driven, as described in the present specification and illustrated in the accompanying drawings which form part of the same.

The invention consists essentially of the novel features pointed out broadly and specifically in the claims for novelty following a description containing an explanation in detail of an acceptable form of the invention.

The objects of the invention are to provide a wringer having safety means whereby the rollers may be released quickly in case of emergency or for other reasons; to produce a wringer retaining a minimum compression in the springs when the rollers are released; to furnish a wringer having a low and compact frame, thereby increasing the length and working range of the screw and spring unit and adding greater flexibility in compression, and overcoming the necessity of frequently readjusting the screw; to supply a wringer with the rollers so adjusted and mounted thereupon to allow easy cleaning of the rollers and releasing of the goods entangled or caught therebetween; and generally, to manufacture a durable and economical wringer that will accomplish the aforesaid purposes.

In the drawings, Figure 1 is a front elevation view of the wringer, showing parts in section.

Figure 2 is a side view showing parts in section.

Figure 3 is a fragmentary plan view, showing the screw in section.

Figure 4 is a fragmentary side view showing the threaded block disengaged from the screw.

Figure 5 is a partial section of the bearing assembly.

Like numerals of reference indicate corresponding parts in the various figures.

45 The wringer frame consists of two end upright posts 10 secured together by two upper cross slats 11 situated near the top thereof and two lower cross slats 12. The cross slats are secured to the posts, as aforesaid, 50 by means of wood screws 13 and tie rods 14.

The posts 10 have a slot 24 in the centre extending downwardly from the top to within a certain distance of the bottom to receive the roller bearing blocks and other parts. The lower portion of the slot is

finished in a semicircle to receive the bearing blocks 18, and a groove or gain 23 of semi-circular cross-section is provided in the posts to receive the ring 20 and the eyebolt 22. The groove or gain 23 extends over the entire inside surface of the slot 24. Gussets 15 are provided at the top of the posts and secured thereto by wood screws in order to strengthen the posts and render them more rigid against bending or vibrating. The frame can be suitably mounted upon a tub or other object by any suitable means such as clamps, etc.

Two rollers 16 and 17 are mounted upon the posts vertically one above the other, the lower roller 16 being rigidly mounted thereupon, while the upper roller is slidably mounted.

The lower roller 16 is rigidly mounted upon a shaft 27 rotating in semi-circular blocks 18 and 19; the blocks are rigidly mounted in the slot 24. A metallic ring of semi-circular section 20 encircles the bearing blocks 18 and 19, and has two straight ends adapted to be tied together by means of a collar and the pin 21. The ring fits into the groove or gain 23 whereby it is held against lateral movement. The shaft 27 projects outside of the frame and a suitable pulley or hand crank can be mounted thereupon.

60 is a flat piece of metal inserted between the lower portions of the ring 20 and partly into the bearing block 18 to prevent any rotation of the bearing blocks 18 and 19.

Washers 28^A are loosely mounted upon the shafts 27 and 28 between the ends of the rollers and the inside surface of the posts.

The upper roller 17 is rigidly mounted upon the shaft 28 which rotates in semi-circular bearing blocks 25 and 26. The blocks are slidably mounted in the slot 24 and are held together by means of the eyebolt 22.

The eyebolts are made of half-round metal; a hole is provided at the top for the cotter pin 29. 100

30 is the floating member mounting the pressure regulating and releasing means. It is supported at the ends by the metallic clips 30^A which are mounted upon the springs 32. The member 30 is situated between the upper slats 11 and enough clearance is provided to allow the member to move upwardly and downwardly without coming in contact with the slats 11. One leg of the clip 30^A supports one end of the

floating member 30, to which it is secured by means of bolts 33, and the other leg rests upon the top of the spring 32. A hole is provided in the upper leg of the clip through which the eyebolt 22 passes.

Collars 34 are secured to the upper part of the eyebolts 22 to which they are secured by means of the cotter pins 29. A washer 35 made of rubber or other resilient material is inserted between the collar 34 and the upper leg of the clip 30^A, for absorbing the impact when the cross member is suddenly released upwardly.

36 is the screw whereby the pressure upon the rollers can be adjusted. It is carried in the bearing plate 37 which is secured to the underside of the upper slats 11 by means of wood screws 38. The screw 36 has a collar or head at its lower end rotatably mounted in the bearing plate 37, and a hole situated just above the top part of the bearing plate through which a cotter pin 39 is inserted.

The screw is supported at the bottom as explained hereinbefore, and rotates at the top in a U-shaped housing 40 which is secured to the top surface of the floating member 30 by means of wood screws 41. The threads on the screw are preferably cut to less than a full thread on the outside or end of the thread. This is to prevent the thread from becoming burred when pressed against the housing while sliding or turning.

The threaded block 49 being hingedly supported at its lower end must necessarily have a shorter stroke or throw towards its base. The threads must therefore be correspondingly shorter in depth in the lower threaded portion of the nut part. With reference to the structure of the threads on a screw and its companion nut, it is hereby clearly pointed out that the exposed or outer end of the standard thread on a screw is of greater circular diameter than the exposed or inwardly projecting end of a thread when cut on its companion the nut; it therefore necessarily follows, that while the threads are of the same pitch, the threads must be cut with a greater swing diameter when cut upon the quadrantal face of a nut part which must necessarily be disengaged from its companion the screw in the abnormal manner of shifting laterally out of mesh while under tension. The threads on the nut part must be machined so as to finish with a tip diameter or curvature corresponding to the diameter or curvature of the tip or end of the threads upon its companion the screw. The threads on the screw 36, and the threaded block 49 are therefore modified to assure of their respective threads disengaging from each other at all points of contact simultaneously. This thread is of such special form and shape that it might properly be called "a lateral disengaging thread".

45 is the hand crank actuating the screw 36. It is threaded upon the screw and secured by means of a castle nut 46 and a cotter pin 47. A washer 48 made of rubber or some other resilient material, is inserted around the screw between the bottom surface of the hand crank 45 and the housing 40.

49 is the threaded block pivotally mounted in the housing 40 which in turn is secured within the floating member 30. It has a portion threaded to engage the screw, and is engaged and disengaged by operating the lever 50. The lever 50 pivots on a rivet or on a pin secured to the housing 40. One end of the lever connects with links 57 which in turn connect with the top portion of the threaded block 49. By forcing the lever 50 downwardly, that is, in the position shown in dotted lines on Figure 1, the links 57 are tilted and the threaded block 49 is pulled out of engagement with the screw 36. The releasing lever has a hole therein forming a seat upon which the spring 52 rests. A seat is also provided in the bearing block in which the other end of the spring 52 rests. The spring tends to force the lever out and maintain the bearing block in engagement with the screw 36; the links are then in a horizontal position.

When goods become entangled in, or wind around, the rollers, the lever 50 is pushed downwardly, the links 57 pull the threaded block out of engagement with the screw, and the floating member 30 moves upwardly and releases the pressure upon the top roller. A drain board may be suitably located under the lower roller.

As will be seen in Figure 1, the eyebolts 22 will raise the upper roller 17 when the floating member 30 is raised by means of the screw 36. But when the threaded block 49 is disengaged from the screw, the floating member will drop down until the upper roller rests upon the lower roller 16. As the springs 32 are subjected to a predetermined pressure by means of the collar 34 and the cotter pin 29, wringing can be effected without operating the screw 36. If, however, more pressure is required upon the rollers, it can be quickly increased by turning the hand crank 45. If the clothes become entangled or wound around the rollers, or if the operator's hand or fingers should become caught between the rollers, the pressure will at once be reduced by simply pressing the releasing lever 50 to the position shown dotted in Figure 1.

What I claim is:—

What a claim is.—

1. In a wringer, a frame mounting a pair of rollers, the lower roller being rotatably and the upper roller being rotatably and slidably mounted in said frame, springs secured between said upper roller and a floating member, a screw rotatably and non-slidably secured to said frame and a hand 130

crank rigidly secured to said screw, and means secured to said floating member for engaging and disengaging said screw.

2. In a wringer, a frame consisting of two slotted end posts and a pair of cross slats rigidly secured thereto substantially at the top and bottom thereof, a pair of rollers mounted in said end members, the lower roller being rotatably and the upper roller 10 being rotatably and slidably mounted in said slot, springs secured between said upper roller and a floating member, a screw rotatably and non-slidably secured to said frame and a hand crank rigidly secured to said screw, and means secured to said floating member for engaging or disengaging said screw.

3. In a wringer, a frame consisting of two slotted end posts and a pair of horizontally 20 arranged cross slats secured thereto substantially at the top and bottom thereof, a shaft rigidly mounting a lower roller and rotating in bearing blocks rigidly secured in said slot, a second shaft rigidly mounting 25 an upper roller rotating in bearing blocks, eyebolts slidably mounted in grooves in said slots and suspending said last-mentioned bearing blocks, springs secured between said upper roller and a floating member, a screw 30 rotatably and non-slidably secured to said frame, and means secured to said floating member for engaging or disengaging said screw.

4. In a wringer, a frame consisting of two slotted end posts and a pair of horizontally 35 arranged cross slats rigidly secured thereto substantially at the top and bottom thereof, a pair of rollers rigidly secured to shafts mounted in bearing blocks, eyebolts encircling the upper bearing blocks and being 40 slidably secured at the top to a floating member, collars rigidly secured to said eyebolts and resilient washers between said floating member and said collars, springs encircling 45 said eyebolts and bearing upon said upper bearing blocks and against said floating member, a screw rotatably and non-slidably secured to said frame and a hand crank rigidly secured to said screw, and means mounted 50 on said floating member for engaging and disengaging said screw.

5. In a wringer, a frame mounting a pair 55 of rollers, the upper roller being free to oscillate in a vertical plane to a limited extent, a floating member associated with springs bearing upon said upper roller, a screw mounted in said frame and engaging a threaded block mounted in said floating member, a hand crank rigidly secured to 60 said screw and a resilient washer secured thereunder, and means in said floating member for effecting disengagement of said threaded block with said screw.

6. In a wringer, a frame consisting of 65 two slotted end posts and a pair of horizon-

tally arranged cross slats rigidly secured thereto substantially at the top and bottom thereof, a lower and an upper roller mounted in said slot, springs secured between said upper roller and a floating member slidably mounted in said slot, a bearing rigidly secured to said cross slats and rotatably and non-slidably mounting a screw, a hand crank rigidly secured to said screw, and means secured to said floating member for 75 engaging and disengaging said screw.

7. In a wringer, a frame mounting a pair of rollers, the lower roller being rotatably and the upper roller being rotatably and slidably mounted in said frame, springs secured 80 between said upper roller and a floating member, a screw rotatably and non-slidably secured to said frame and a hand crank rigidly secured upon said screw, a threaded block pivotally mounted in said floating 85 member and adapted to be normally held in operative engagement with said screw, and means for effecting disengagement of the threaded block with said screw.

8. In a wringer, a frame mounting a pair 90 of rollers, the lower roller being rotatably and the upper roller being rotatably and slidably mounted in said frame, springs secured between said upper roller and a floating member, a screw rotatably and non-slidably 95 secured to said frame and a hand crank rigidly secured to said screw, a threaded block pivotally mounted on the bottom portion of said floating member and having the upper portion thereof threaded to engage corresponding threads in said screw, a lever pivoting in a housing secured to said floating member and adapted to normally hold said threaded block in engagement with said screw.

9. In a wringer, a frame mounting a pair 100 of rollers, the lower roller being rotatably and the upper roller being rotatably and slidably mounted in said frame, springs secured between said upper roller and a floating member, a screw rotatably and non-slidably 105 secured to said frame and a hand crank rigidly secured to said screw, a threaded block pivotally mounted at the bottom portion to said floating member and having a portion thereof threaded to engage corresponding threads in said screw, a lever pivotally mounted in said floating member, links connecting said lever to said threaded block and a spring adapted therebetween 110 to normally effect engagement between said threaded block and said screw and to hold the lever in operative position.

10. In a wringer, a frame mounting a 115 pair of rollers, the lower roller being rotatably and the upper roller being rotatably and slidably mounted in said frame, springs secured between said upper roller and a floating member, a screw rotatably and non-slidably 120 secured to said frame and a hand 125

crank rigidly secured to said screw, a threaded block pivotally mounted in said floating member and adapted to engage said screw and to receive a horizontally arranged spring, a lever pivotally mounted in said floating member and adapted to receive said last-mentioned spring and a pair of links, said links connecting said lever to the upper portion of said threaded block.

11. In a wringer, a frame mounting a pair of rollers, springs associated with said rollers and a floating member bearing thereupon, a screw rotatably and non-slidably mounted in said frame and engaging a threaded block pivotally mounted in said floating member, a lever pivotally mounted in said floating member and associated with said threaded block, and springs posi-

tioned between said threaded block and lever to maintain said threaded block in engagement with said screw. 20

12. In a wringer, a frame mounting a pair of rollers, springs associated with said rollers and a floating member bearing thereupon, a screw rotatably and non-slidably 25 mounted in said frame, a threaded block pivotally mounted on said floating member and engaging said screw, the threads in said screw and block being adapted throughout their threaded portions to simultaneously 30 disengage all engaging surfaces between said threaded members, and means in said floating member for disengaging said threaded block from said screw.

In testimony whereof I affix my signature.
JOHN MARTIN DEAGLE.
